(57) **CLAIM**

The ornamental design for a sanding tool, as shown and described.

DESCRIPTION

FIG. 1 is a top perspective view of a sanding tool according to the invention;

FIG. 2 is a bottom perspective view of the sanding tool of FIG. 1;

FIG. 3 is a rear plan view thereof;

FIG. 4 is a right-side plan view thereof, the left-side plan view being a mirror image thereof;

FIG. 5 is a front plan view thereof;

FIG. 6 is a top plan view thereof; and,

FIG. 7 is a bottom plan view thereof.

The broken line showings of FIGS. 1-7 are for illustrative purposes only and form no part of the claimed design.
